E. L. COPSEY,
VALVELESS ROTARY PUMP,
APPLICATION FILED JUNE 28, 1917.

1,303,169.

Patented May 6, 1919.

UNITED STATES PATENT OFFICE.

EDWIN LAWRENCE COPSEY, OF COLCHESTER, ENGLAND, ASSIGNOR TO F. W. BRACKETT & COMPANY LIMITED, OF COLCHESTER, ENGLAND.

VALVELESS ROTARY PUMP.

1,303,169.

Specification of Letters Patent.

Patented May 6, 1919.

Application filed June 28, 1917. Serial No. 177,551.

To all whom it may concern:

Be it known that I, EDWIN LAWRENCE COPSEY, a subject of His Majesty the King of Great Britain and Ireland, residing at Old Heath, Colchester, in the county of Essex, England, have invented a new and useful Improvement in Valveless Rotary Pumps, of which the following is a specification.

The present invention relates to valveless rotary pumps of the class in which the piston not only rotates around an eccentrically disposed pin secured to the pump casing but reciprocates within a cylindrical hole in the driven element at right angles to the axis of rotation, the driven element thus formed constituting a cylinder, revolving in a casing furnished with suction and delivery ports, and is an improvement in the invention described in Patent No. 1,223,036.

20 The specification above referred to described a valveless rotary pump in which the piston contained in a driven cylinder, is slidably mounted on a non-rotating eccentrically disposed pin secured in the end walls 25 of the casing, said cylinder being driven by a shaft situated externally to the pump casing and provided with driving means co-acting with driving means at or about the periphery of the cylinder.

30 According to the modification described herein, the eccentrically disposed pin about which the piston revolves also acts as the driving shaft for the cylinder and carries means for directly rotating the latter which 35 in turn reciprocates the piston.

In the accompanying drawing which illustrates, as an example, a construction of pump according to the present invention:—

Figure 1 is a longitudinal section on line 40 1—1 of Fig. 2; and

Fig. 2 is a cross section on line 2—2 of Fig. 1.

As in the construction described in the aforesaid specification, the piston 1 reciprocates in an open-ended cylinder 2, the latter revolving in a casing 3 furnished with a suction port 4 and a delivery port 5.

The piston 1, the opposite ends of which are rounded to conform to the wall of the 50 casing 3 is slotted midway between its ends to receive two plates 6, between which works

a roller 7 mounted on a shaft 8 one end of which is supported in a closed bearing 9 formed in the end wall 10, while on the opposite side of the piston the shaft 8 is supported 55 in and passes through a bearing 11 formed in the end wall 12, a stuffing box 13 being preferably provided to prevent the escape of fluid from the interior of the pump.

The shaft 8 is eccentrically disposed with 60 respect to the axis of rotation of the cylinder to a degree equal to a half of the travel of the piston.

The cylinder 2 is furnished on one side with a ring of internal teeth 14 secured to or 65 formed integral therewith, adapted to co-act with teeth provided on a pinion 15 keyed on the shaft 8 the outer end of which is provided with means to enable same to be driven by belt or coupled to an electric motor, or 70 driven by other means.

As shown in the drawing the end wall 10 is made removable, though if desired both ends may be so formed, further, if desired a second ring of teeth may be provided on the 75 other side of the cylinder adapted to engage with a second pinion provided on the shaft 8.

The action of the pump is the same as that of the pump described in the aforesaid prior specification and need not be further described herein.

What I claim is:—

1. In a valveless rotary pump, the combination of a casing, an eccentrically disposed driving shaft, a cylinder located in said casing and adapted to rotate around said driving shaft, a toothed element on said driving shaft, a long bearing for said shaft located on both sides of said casing, an internally toothed element on the driven cylinder adapted to co-act with the toothed element on the driving shaft, a piston reciprocating in and rotating with said cylinder, and a slot provided in said piston midway between its ends in which said driving shaft is adapted to 95 slide during the rotative movement of the piston.

2. In a valveless rotary pump, the combination of a casing, an eccentrically disposed driving shaft, a roller mounted on said shaft, 100 a cylinder located in said casing and adapted to rotate around said roller, a toothed ele-

ment on said driving shaft, a long bearing for said shaft located on both sides of said casing, an internally toothed element on the driven cylinder adapted to co-act with the 5 toothed element on the driving shaft, a piston reciprocating in and rotating with said cylinder, a slot provided in said piston mid-

way between its ends and plates secured within said slot between which said roller is adapted to slide during the rotative movement of the piston.

In witness whereof I have hereunto set my hand.

EDWIN LAWRENCE COPSEY.
